TYPE-WRITING MACHINE.

942,113.

Specification of Letters Patent.

Patented Dec. 7, 1909.

Application filed September 18, 1907. Serial No. 393,439.

To all whom it may concern:

Be it known that I, ANDREW W. STEIGER, a citizen of the United States, and resident of Bridgeport, in the county of Fairfield and State of Connecticut, have invented certain new and useful Improvements in Type-Writing Machines, of which the following is a specification.

My invention relates especially to the tabulating mechanism of typewriting machines and has for its object to provide improved mechanism of the class specified.

To the above and other ends, the invention consists in the features of construction, combinations of devices and arrangements of parts hereinafter described and particularly pointed out in the claims.

My invention is shown as applied to a Remington typewriter, but it is to be understood that the nature of the invention is such that it may be adapted to other styles of writing machines.

One form of the invention is shown in the accompanying drawings, wherein—

Figure 1 is a vertical, front-to-rear, sectional view taken about centrally of a Remington typewriter and showing my invention applied thereto, parts of the machine being omitted and parts broken away. Fig. 2 is a rear elevation of the machine, parts being omitted and parts being broken away. Fig. 3 is a fragmentary horizontal sectional view taken on a plane between the top plate and the base. Fig. 4 is a front vertical sectional view showing the tabulator key levers and some of the associated parts.

In the drawings, the main frame of the machine is shown as comprising a base 1, corner posts 2 and a top plate 3. A set of type bars are circularly arranged on the top plate, each type bar 4 being connected by a link 5 with a key lever 6 pivoted at the rear of the base. The type bars when actuated coöperate with the under surface of a platen 7 mounted in a platen carriage comprising a platen frame 8 pivotally supported on a truck 9. The truck is provided with rollers 10 which run on a fixed guide rod 11 and with a slide which coöperates with a rear fixed guide rod 11^a. A roller 12 at the front of the platen frame coöperates with a front shift rod 13 which is supported in the usual way on pivoted arms 14. A carriage feed rack 15 is secured to arms 16 pivoted at 17 to the carriage truck. Said rack is normally

spring-pressed into engagement as usual with a feed pinion 18, the latter being operatively connected with a toothed escapement wheel 19 coöperative with which are escapement dogs 20 arranged at the top of a pivoted dog carrier or rocker 21. The dog rocker is connected with a universal bar by a train of mechanism comprising a link 22, a bell crank lever 23, a second link 24, a crank arm 25 of a rock shaft 25^a having arms 26 from which depend arms 26^a which are connected directly with the universal bar 27 which underlies the set of key levers 6. The parts above briefly described are not of my invention and are found in the Remington machine and need not be more fully described at this place.

Referring more particularly to the tabulating mechanism, this comprises a stop rack-bar 28 supported on angular arms 29 suitably secured to the carriage truck 9. One or more carriage or column stops 30 are detachably secured to the rack bar and coöperative with these stops are a set of denominational stops 31 which, as herein shown, project forward from and are integral with the upper ends of a set of upright denominational levers 32 arranged side by side and having open mouth bearings by which they pivotally engage between their ends a fulcrum rod 33 mounted in a hooded frame or supporting bracket, said frame being suitably secured at the rear of the machine. The levers 32 extend straight down from their pivots through an opening in the base of the machine. The forward edge of each lever 32 is curved at 32^a substantially concentric with the pivot 33 and a detachable pin 33^a extends across the frame 34 near the curved portions of the levers so as to afford a turning of the levers on their pivot pin or rod but to prevent an accidental displacement of the levers from said pivot pin. The frame 34 is detachable but the mode of attaching it is the invention of another and need not be described in detail.

While I have shown the denominational stops 31 as integral with the levers 32 it is to be understood that they may be separate parts suitably connected if so desired. The denominational levers and stops are suitably guided and are adapted to be actuated by novel mechanism presently to be described. When so actuated they coöperate with a cross bar 35 supported on arms 36 pivoted at 110

37 to the frame 34. One of the arms 36 has a forwardly extending horizontal arm 38 which carries an adjustable abutment 39 co-operative with a release lever 40. Said release lever is pivoted at 41 to a bracket 42 secured to the top plate and is provided at its forward end with an off-set lifting shoe 43 bifurcated to straddle the feed pinion 18 so as to provide a lifting member at either side of the pinion and normally underlying and just out of contact with the feed rack 15. When the bar 35 is pushed forward by one of the denominational levers 32 the abutment 39 will press down the rear arm of the lever 40, elevating the lifting shoe 43 and causing it to swing the rack 15 upward out of mesh with the pinion 18, thereby releasing the carriage from its escapement mechanism and permitting it to be drawn freely leftward across the top plate under the influence of the usual spring drum 44 with which the carriage is connected by a band or strap 45. The tabulating mechanism as thus far described is not *per se* of my invention and it is not thought a more detailed description is necessary.

Referring now to the novel actuating mechanism for the tabulating mechanism, this mechanism comprises for each denominational stop lever 32 a member, bar or floating key lever or one having a fulcrum or fulgurum point, the position whereof varies during the operation of the key lever, said key lever, member or bar being designated as a whole by the numeral 46 and comprising a forward horizontally disposed portion provided with a key 47, a vertically disposed portion extending downward and slightly rearward from the forward horizontal portion and connecting at its lower end with a rearwardly extending horizontally disposed portion 46^a which is pressed laterally outward as indicated at 46^b to provide a longitudinally extending strengthening rib. The rear end portion of the part 46^a is folded over to form a hole, the interior of which is threaded and receives the forward threaded portion of a rod 48, said rod being adjustably connected with the lever 46 and being held in fixed relation therewith by a check nut 49. The rear end portion of the rod 48 is flattened as indicated at 48^a and carries a laterally extending pin 50 which enters a hole in the lower arm of the associate lever 32 near its end. A spring clip 51 is secured to the rod 48 and cooperates with the free end of the pin 50 to prevent accidental separation of the detachable connection between the lever 32 and the rod 48. As will be best seen in Fig. 2, the upper arms of the levers 32 are arranged a letter space distance apart but the lower arms are curved or spread laterally at varying degrees as indicated at 32^b so that the lower arms of the levers 32 are spaced sufficiently

far apart to permit the connections of the rods 48 and levers 46 to be arranged side by side without causing interference between said rods, levers and connections. The curved portions 32^b of the levers 32 are 70 or may be strengthened by curved strips 32^c of metal suitably secured to said levers.

Each lever 46 is pivoted on an arm or guide link 52, said arm being formed preferably of sheet metal and having vertical side portions 52^a which at the rear incline toward each other so as to lie close to or embrace the associate lever 46 at its vertically disposed part, said arm and said lever being pivotally connected as by a rivet or pin 53 passing from one portion 52^a to the other through the lever 46. The arms 52 are inclined to the horizontal and, in the present instance, extend downwardly and forwardly from the pivot pins 53 toward the front 85 of the machine. The side portions 52^a of each of said arms incline laterally away from each other from rear to front and are perforated at their forward end portions to receive a pivot rod 54. Said pivot rod is 90 secured at its ends by screws 55 in angular bracket 56, the horizontal portions of said brackets being provided with slots 57 which receive securing screws 58, said securing screws entering the base frame and thereby 95 detachably and adjustably securing the brackets 56 and the pivot rod 54 in a fixed relation with the machine frame. The construction is such that when the key 47 is operated it moves nearly straight downward, whereas the rear end of the bar 46 moves toward the rear of the machine. The forward and rear ends of the bar 46 move in paths that are nearly at right angles to each other. The construction is such that 100 the spreading or divergence of the side portions 52^a of the arms 52 provides a broad and stable bearing for each arm on the pivot rod 54 and at the same time tends to maintain the arms 52 properly spaced apart. As 105 shown in Fig. 3 the levers 46 fan or diverge from rear to front. The forward horizontal portions of said levers pass through guide slots in a combined guide and cover plate 59 which is secured by screws 110 60 to the brackets 56, the upper portion of said plate being rearwardly inclined and formed with a slot 61 through which the usual or a suitable tabulator scale 62 may be 115 inspected, said scale being suitably attached to the guide and cover plate 59. The detail construction of the scale is not my invention and need not be described. By loosening the screws 58 the guide plate may be 120 adjusted laterally of the levers 46.

The lower part of the vertically disposed portion of each lever 46 is guided in the slot formed in a guide or comb plate 63, said comb plate being secured at its ends to angular brackets 64 fastened by screws 65 to 125

the inner sides of the base. Each bracket is formed with a slot for the free passage of a headed screw 66, said screw passing through the slot in the bracket and entering a threaded hole in the comb plate 63. By making the guide plate 59 and the comb plate 63 adjustable, the accurate assemblage and adjustment of the levers 46 in the machine is facilitated. The bracket is engaged beneath 10 by the comb plate and above by the heads of the screws 66, the construction being such that by loosening the screws 66 the comb plate may be adjusted laterally of the levers 46. Each lever 46 is provided with a helical 15 restoring spring, said spring being secured at one end to the horizontal arm 46^a and at the other end to the guide or comb plate 63. The spring tends to maintain the lever 46 in the position shown in Fig. 1, the forward 20 horizontal portion of said lever abutting against the closed end of the slot 58 in the plate 59. Each of the levers 46 is provided with a projection or abutment 46^a which is adapted when the lever is operated to contact with the top of the comb plate 63 and 25 limit the depression of said lever. It will be understood that the lever 46 and the rod 48 constitute in effect a single member, said member or lever being pivotally connected 30 directly to the denominational lever 32 and also to the associate arm 52 and being provided with means (i. e. the screw connection between the lever 46 and rod 48) for varying its length.

35 When any finger key 47 is depressed to operate its lever 46, the associate arm 52 will be turned downward about its pivot or fulcrum 54 and the pivot 53 being above the horizontal will move in an arc or path which 40 will curve downward and rearward. Because of this movement of the pivot 53 the lever 46 as a whole will move rearward, while its forward end is receiving a downward movement, forcing the lower arm of 45 the associate lever 32 rearward and the upper arm of said lever 32 forward, projecting the associate stop 31 into the path of the carriage or column stop or stops 30 and effecting the release of the carriage. The 50 downward movement of the lever 46 will be finally arrested by the contact of the stop 46^a with the comb plate 63. When the depressed key lever 46 is released the associate spring 55 will restore the lever 46 and arm 52 to the positions shown in Fig. 1.

It will be seen that by my invention I provide simple and efficacious actuating devices for the tabulating mechanism; that said devices comprise tabulating key bars or 60 levers each of which is movable at one end in one direction, means being provided to cause the lever to move in another direction substantially at right angles to the first direction when the end of the lever is so moved; that said means in its preferred form

includes a pivoted arm 52; that the actuating devices comprise few parts and are controlled by a set of depressible keys which are arranged above and slightly to the rear of the regular keyboard of the machine so 70 that they will not interfere with the operation of the regular keys; and that the floating tabulating key levers extend from their keys at points above the printing key levers downward between the printing key levers 75 and to points beneath the same where they are connected with the denominational levers which extend downward between the printing key levers to points beneath the same.

My invention has been embodied in a complete machine in which the parts and elements above stated to have been invented by others, and more especially the tabulator supporting frame and the tabulator scale devices, are shown, and I have preferred to 80 make use of said machine to illustrate my invention, it being understood that I specifically disclaim the parts not invented by me.

Each bar or element 46 is provided below 90 the abutment 46^a with an edge 46^b. By disconnecting the arm 52 from the associate bar 46 at the pivotal point 53 the edge 46^b may be caused to coöperate with the closed end of the associate slot in the comb plate 63, 95 acting as a cam when the associate key 47 is depressed to force said bar 46 rearward as a whole. The operation when the arm 52 is connected with the bar or lever 46 is, however, easier and smoother.

Various changes besides those noted may be made in my invention without departing from the scope thereof.

What I claim as new and desire to secure by Letters Patent, is:—

1. In a typewriting machine and in a tabulating mechanism, the combination of a carriage, a stop thereon, an upright lever of the first order, a tabulator stop operatively connected with the upper arm of said lever, a second lever disposed at an angle to said upright lever and having one arm directly connected with the lower arm of said upright lever, the other arm of said second lever being provided with a key button, and a guide link pivotally connected with said second lever and having a fixed axis of rotation.

2. In a typewriting machine and in a tabulating mechanism, the combination of a carriage, a carriage stop, a coöperating stop, a lever connected with said coöperating stop, and a depressible key lever connected with the first named lever and having a fulcrum the position of which varies during the depression of said key lever.

3. In a typewriting machine and in a tabulating mechanism, the combination of a carriage, a carriage stop, a coöperating stop, a lever for actuating said coöperating stop,

- said lever having a fixed fulcrum, and a key lever directly connected to the first recited lever, said key lever having a moving fulcrum.
5. 4. In a typewriting machine and in a tabulating mechanism, the combination of a carriage, a stop thereon, a coöperating stop, a lever for actuating said coöperating stop, said lever having a fixed fulcrum, a pivoted arm, and a key lever pivotally connected with said arm and with the first recited lever.
5. In a typewriting machine and in a tabulating mechanism, the combination of a carriage, a stop thereon, a coöperating stop, a lever for actuating said coöperating stop, said lever having a fixed fulcrum, an arm having a fixed pivot, and a key lever pivotally connected both to said arm and to the first recited lever.
6. In a typewriting machine and in a tabulating mechanism, the combination of a carriage, a stop thereon, a coöperating stop, an upright lever of the first order having its upper arm connected to said coöperating stop, an arm pivoted to a fixed part and normally at an angle to the horizontal, and an angular key lever pivotally connected at its rear directly to the lower arm of said upright lever, said angular lever being also pivotally connected directly to said arm.
7. In a typewriting machine and in a tabulating mechanism, the combination of a carriage, a stop thereon, a coöperating stop, an upright lever of the first order having its upper arm connected to said stop, an arm pivoted to a fixed part and normally at an angle to the horizontal, and an angular key lever having two horizontally disposed portions and a substantially vertically disposed portion joining the two horizontally disposed portions, the vertically disposed portion of said key lever being pivotally connected to said arm and the rear end of said key lever being pivotally connected with said upright lever.
8. In a typewriting machine and in a tabulating mechanism, the combination of a carriage, a carriage stop, a set of denominational stop levers having fixed fulcrums, and a set of depressible key levers connected with said denominational stop levers, said key levers having moving fulcrums.
9. In a typewriting machine and in a tabulating mechanism, the combination of a carriage, a carriage stop, a set of denominational stop levers having fixed fulcrums, a set of pivoted arms, and a set of key levers each pivotally connected with one of said arms and with one of said denominational stop levers, a pair of guide or comb plates co-operating with said key levers to guide them, stops to limit the movements of said key levers in both directions, and a restoring spring for said key levers.
10. In a typewriting machine and in a tabulating mechanism, the combination of a carriage, a carriage stop, a set of upright denominational stop levers arranged side by side and pivoted between their ends to a fixed part, a set of arms pivoted to a fixed part and normally at an angle to the horizontal, and a set of angular key levers each pivotally connected at its rear directly to the lower arm of one of said denominational stop levers, each of said levers being also pivotally connected directly to one of said arms.
11. In a typewriting machine and in a tabulating mechanism, the combination of a carriage, a stop thereon, a coöperating stop, a lever for actuating said coöperating stop, said lever having a fixed fulcrum, a pivoted arm, a key lever pivotally connected with said arm and with the first recited lever, a plurality of guides for said key lever, said guides being adjustable laterally of said key lever, and a restoring spring for said key lever.
12. In a typewriting machine and in a tabulating mechanism, the combination of a carriage, a stop thereon, a coöperating stop, a lever for actuating said coöperating stop, said lever having a fixed fulcrum, a pivoted arm, a key lever pivotally connected with said arm and with the first recited lever, guides for said key lever, and stops to limit its movements in both directions.
13. In a typewriting machine and in a tabulating mechanism, the combination of a carriage, a carriage stop, a set of denominational stop levers having fixed fulcrums, a set of pivoted arms, a set of key levers each pivotally connected with one of said arms and with one of said denominational stop levers, and a pair of guide or comb plates co-operating with said key levers to guide them, said guide or comb plates being adjustable laterally of said key levers.
14. In a typewriting machine and in a tabulating mechanism, the combination of a carriage, a carriage stop, a set of denominational stop levers having fixed fulcrums, a set of pivoted arms, a set of key levers each pivotally connected with one of said arms and with one of said denominational stop levers, and stops to limit the movements of said key levers in both directions.
15. In a typewriting machine and in a tabulating mechanism, the combination of a carriage, a carriage stop, a set of denominational stop levers having fixed fulcrums, a set of pivoted arms, a set of key levers each pivotally connected with one of said arms and with one of said denominational stop levers, a pair of guide or comb plates co-operating with said key levers to guide them, stops to limit the movements of said key levers in both directions, and a restoring spring for said key levers.
16. In a typewriting machine and in a tabulating mechanism, the combination of a carriage, a column stop, tabulating key levers, guiding means to give each key lever a

- a downward and bodily rearward movement when its key is depressed, and denominational stops controlled by said key levers.
17. In a typewriting machine and in a tabulating mechanism, the combination of a carriage, a column stop, a coöperating stop, a lever connected with said coöperating stop and adapted to operate it, said lever being movable in one direction by hand at or near one end, and guiding means coöperating with said lever so that when so moved the lever as a whole will be moved bodily in a direction substantially at right angles to the first named direction.
18. In a typewriting machine and in a tabulating mechanism, the combination of a carriage, a carriage stop, a coöperating stop, a tabulator key lever operatively connected therewith, and means for causing said key lever when its key is pressed in one direction to move bodily in another direction.
19. In a typewriting machine and in a tabulating mechanism, the combination of a carriage, a carriage stop, a coöperating stop, a tabulator key lever operatively connected therewith, and means for causing said key lever when its key is pressed in one direction to move bodily in another direction, the latter direction being substantially at right angles to the first named direction.
20. In a typewriting machine and in a tabulating mechanism, the combination of a carriage, a carriage stop, a coöperating stop, an upright lever operatively connected at one arm with said stop, and a key lever connected with said upright lever at its other arm and extending toward the front of the machine, the forward end portion of said key lever being depressible, and means for causing said key lever as its forward end is depressed to move bodily rearward.
21. In a typewriting machine and in tabulating mechanism, the combination of a carriage, a stop thereon, a coöperating stop, a lever for controlling said coöperating stop, a floating bar operative near one end on said lever, a key connected with the front of said bar, and means for guiding and controlling said bar so that when said key is operated the end portions of said bar move at angles to each other.
22. In a typewriting machine and in a tabulating mechanism, the combination of a carriage, a stop thereon, a coöperating stop,
- a lever for controlling said coöperating stop, 55
a bar connected at its rear end to said lever, a key connected with the forward end of said bar, and means for guiding the forward portion of said bar in a downward direction when said key is operated and for guiding the rear portion of said bar in a fore and aft direction when said key is operated:
23. In a typewriting machine and in a tabulating mechanism, the combination of a carriage, a carriage stop, a coöperating stop, 60
an upright lever for controlling said coöperating stop, a key bar connected at its rear end to said upright lever and having at its forward end a key, and means for guiding said key bar to cause its rear end to move in 70
a fore and aft direction when said key is depressed.
24. In a typewriting machine and in a tabulating mechanism, the combination of a carriage, a carriage stop, a coöperating stop, 75
an upright lever for controlling said coöperating stop, a key bar pivoted at its rear end to said upright lever and having at its forward end a key, and a guide link pivoted to said key bar and arranged to translate a 80
downward motion of said key into a fore and aft motion of the rear end of said bar.
25. In a typewriting machine and in a tabulating mechanism, the combination with a carriage, printing instrumentalities, a series of fore and aft extending key levers for operating said printing instrumentalities, carriage stops, a set of coöperating denominational stops, upright levers for controlling said denominational stops, said levers extending downward to the base of the machine, a set of key bars pivoted at their rear ends to the lower ends of said levers and extending toward the front of the machine and fanning outward beneath said key levers, 90
said key bars near their forward ends extending upward between said key levers and into the keyboard of the machine, and keys for operating said key bars. 95

Signed at the borough of Manhattan, city 100
of New York, in the county of New York
and State of New York, this 16th day of
September, A. D. 1907.
